UNITED STATES PATENT OFFICE.

LEON FREIDENRICH, OF NEW YORK, N. Y.

SUPPLEMENTARY WAISTBAND FOR PANTS.

SPECIFICATION forming part of Letters Patent No. 333,064, dated December 22, 1885.

Application filed December 11, 1883. Serial No. 114,222. (No model.)

To all whom it may concern:

Be it known that I, LEON FREIDENRICH, a citizen of the United States, residing at New York, in the county and State of New York, have invented a new and useful Improvement in Wearing-Apparel, of which the following is a specification.

My improvement relates to boys' pants, and has for its object to provide on such garments elasticity at the waist thereof, as hereinafter described and claimed, reference being made to the accompanying drawings, in which similar letters of reference indicate like parts on each figure.

15 My improvement is designed for application to that class of boys' pants which are worn without suspenders, and are connected either to a shirt-waist or direct to a jacket or the like.

In the drawings, Figure 1 represents a supplementary band provided with my improvement, in practice attached inside the upper part 20 of boys' pants at the waist thereof. Fig. 2 represents a similar band embodying my improvement illustrated as sewed onto the waist of a 25 pair of boy's pants, showing part of the ordinary waist-lining and a portion of the garment fabric. Fig. 3 represents a blank band-piece adapted to receive an elastic. Fig. 4 represents a pair of pants with my improvement attached thereto.

A is a supplemental band made of textile cloth or like inelastic material, provided with button-holes *a* or analogous fastening devices. When such supplementary band is provided 35 with a series of downwardly-extending elastic strips or the like, as has heretofore been practiced, it is requisite that its lower edge, *a'*, shall be unattached its whole length, or nearly so, to the waistband-lining C. This is an objectionable feature which is overcome by my invention.

B is a piece of material elastic in the direction of the arrow (not lengthwise) inserted in apertures *b*, of suitable shape, formed upon and 45 into the blank from which the supplementary band A is constructed. (See Fig. 3.) The elastic B may be of any desired form; but at its center it is required to be greater in depth than at its end, as plainly shown in the drawings. It may be curved toward its center, said 50 curved part composing either its upper or lower line; (the latter form is indicated in dotted

lines, Fig. 1;) or it may be a triangle with its inclined sides at top or at bottom, the latter form being indicated on aperture *b*, Fig. 3; or 5; independent pieces B may be inserted in separate apertures, as shown in Fig. 2, in which case the central piece is to be the larger one, for a purpose hereinafter set forth.

I will observe that on boys' pants it is only 60 necessary to secure elasticity under tension to the rear of the waist—say at about the space between letters *l l*, Fig. 4.

In carrying out my invention I first prepare a blank strip of material and cut out bodily 65 therefrom a piece or pieces thereof. (See *b*, Fig. 3.) Within said apertures I then insert a piece or pieces, as the case may be, of elastic, B, and firmly stitch the same in place. The band A, with said elastics in place, is turned 70 over and hemmed at its upper and lower edges, and the lower edge, *a'*, is then stitched along its full length to the waistband-lining C, above the fabric D of which the garment is composed. By this construction I provide required 75 elasticity directly under the rear group of fastening devices, and secure a greater degree of elasticity toward the center of said group, whether I employ a single elastic, as shown in Fig. 1, or separate pieces, as shown in Fig. 2. 80

By the attachment of the supplementary band A along the full length of its lower hemmed edge, *a'*, to the waistband-lining C, I secure great strength, and said band A at its lower edge is always maintained in its normal position, thus doing away with the puckering gaps that in operation occur in all analogous devices wherein the main part of the lower edge, *a'*, is left unattached. Furthermore, by this construction I do away with all stay-pieces or 85 welts heretofore employed, and which, by being attached to the fabric D, inside the seat of the pants, present an unsightly appearance, involve labor and expense, and have the tendency to rip or stretch said fabric at a point 90 where the greatest strength is required. Such connections also to such lower welts have the effect to pull up into unsightly baggy folds all the fabric D between the points of tension, for when said welts are employed the lower 95 edge, *a'*, of the supplementary band A must be normally detached nearly its whole length.

Having now fully described my invention, what I claim is—

1. A supplementary waistband for pantaloons, provided with suitable fastening devices composed of a strip of textile material having inserted bodily therein, within apertures *b*, a piece or pieces of elastic material deeper in width at the center and tapering therefrom to either end, said band *A* having its lower edge, *a'*, stitched its full length to an underlying waistband-lining, *C*, as and for the purpose intended, substantially as described.
2. In a supplementary waistband for boys' pants, an inelastic strip, *A*, having cut out from its body one or more apertures, *b*, said

apertures being supplied with elastic pieces *B*, having the greater depth at their centers 15 and tapering therefrom to their side ends, said strip *A*, constructed as described, being attached along its lower edge, *a'*, to the waistlining *C*; all in combination with the rear portion of a pair of boy's pants, as and for the 20 purpose intended, substantially as described.

LEON FREIDENRICH.
